UNITED STATES PATENT OFFICE.

GUSTAV A. MITTENDORF, OF NEW BRAUNFELS, TEXAS.

SADDLE-TREE FORK.

SPECIFICATION forming part of Letters Patent No. 224,709, dated February 17, 1880.

Application filed November 6, 1879.

To all whom it may concern:

Be it known that I, GUSTAV ADOLPH MITTENDORF, of New Braunfels, in the county of Comal and State of Texas, have invented a new and useful Improvement in Saddle-Forks, 5 of which the following is a specification.

Figure 1 is a perspective view of my improved saddle-fork. Fig. 2 is a sectional side elevation taken through the line *x x*, Fig. 1. 10 Fig. 3 is a sectional plan view taken through the line *y y*, Fig. 2.

Similar letters of reference indicate corresponding parts.

The object of the invention is to strengthen 15 the iron fork by means of a bent wooden part, as hereinafter described.

A represents the side bars of the saddle-tree, about the construction of which there is nothing new.

20 *B* is the iron part of the fork, the arms of which are made narrow and the neck hollow.

Upon the forward edge of the inner surface of the arms of the fork *B* is formed a rib, *C*, which extends from the ends of the arms to the arch of the fork. 25

Upon the middle part of the inner surface of the arms of the fork *B* is formed a second rib, *D*, which extends from the ends of the arms to and through the cavity of the neck of the fork *B*. 30

The ribs *C D* strengthen the fork and allow

it to be made lighter than would otherwise be practicable. The extension of the rib *D* into and through the cavity of the neck strengthens the neck against the strain when a lasso is 35 used.

E is the forward part of the saddle-fork, which part is made of hard strong wood bent into *U* form and worked out into proper shape. The wooden part *E* is secured to the 40 side bars, *A*, by screws or rivets, and greatly strengthens the fork without materially increasing its weight.

Another advantage of the wooden part *E* is that it may be readily made narrower or wider, 45 as may be desired.

F is the pommel, which is made of wood and of any desired shape, and is secured to the neck of the fork *B* by screws or rivets.

I am aware that the arms of forks have 50 been provided with flanges or ribs extending their entire length; but

What I claim is—

In saddle-tree forks, the combination, with the iron fork *B*, of the bent wooden part *E*, 55 substantially as herein shown and described, to give the fork *B* additional strength, as set forth.

GUSTAV ADOLPH MITTENDORF.
